UNITED STATES PATENT OFFICE.

FARNUM F. DORSEY, OF ROCHESTER, NEW YORK, ASSIGNOR TO NORTH EAST ELECTRIC COMPANY, OF ROCHESTER, NEW YORK, A CORPORATION OF NEW YORK.

SPEEDOMETER.

Application filed March 26, 1927. Serial No. 178,758.

This invention relates to speedometers of the type in which a cup-like pivotally mounted indicator, with a depending skirt of electrically conductive material, is turned, 5 against the opposition of a spring, by the inductive effect of a stationary magnet and a rotary armature, the movement of the indicator being proportionate to the speed of rotation of the armature.

10 In a speedometer mounted upon the instrument-board of a motor vehicle it is usually desirable that the drive-shaft extend from the rear of the instrument either in a horizontal position or in a position at a considerable 15 angle with the vertical. It is also desirable that the pivot-bearings of the indicator be mounted on fixed supports on the frame of the instrument. To secure these advantages in instruments of the forms previously used, 20 it has been necessary to introduce various complications into the structure, such as gears or flexible shafts, to connect the drive-shaft with the rotor, and overhanging arms to support the pivot-staff bearings and the 25 indicator.

The object of the present invention is to secure the advantages of a rear-driven instrument while avoiding the disadvantages just referred to, particularly the use of gearing 30 or sharply curved flexible shafts. To this end the indicator, magnet and rotary armature are so formed and related that they have certain approximating and overlapping portions sufficient for their functional cooperation, 35 altho the pivotal axis of the indicator and the axis of rotation of the armature are arranged at such an angle that the armature may be mounted directly upon a rearwardly-extending drive-shaft.

40 In the accompanying drawings, Fig. 1 is a sectional side elevation of a speedometer embodying the present invention, and Fig. 2 is a section on the line 2-2 in Fig. 1.

The invention is illustrated as embodied in 45 an instrument having an indicator 3, drawn from some conductive sheet material such as aluminum, in the form of a truncated cone. This indicator is fixed to a pivot staff 4 which is upwardly and forwardly inclined at an angle of 45°. The staff has bearings mounted in stationary frame members 5 and 6, and the usual hair spring 7, attached to the staff, tends to hold the indicator normally in zero 50 position. The conical skirt of the indicator

has the usual graduations to indicate speed 55 in miles or kilometers per hour, which are visible through an opening in the face plate or dial 8 of the instrument. This dial may be covered with glass 16 in the usual manner.

The instrument has a cylindrical housing 18, of which the rear wall is shown as embodied in a casting 9 comprising part of the frame of the instrument. Upon this rear frame member is supported a permanent magnet 10 in the form of an open ring, the 60 opening being at the top of the magnet so as to provide, at that point, two polar extremities 11. The armature 12 is in the form of a disc of sheet steel or other suitable magnetic material, having at its periphery a series of 65 rearwardly projecting fingers 14. This armature is fixed to and actuated by a horizontal drive shaft 13 which turns in bearings in the frame member 9.

The axis of the armature is so located that 70 the upper part of the armature approaches close to the lower surfaces of the polar extremities 11. The indicator is so mounted that the rear part of its conical skirt projects into the space between the magnet and the 75 armature. For some distance near the polar extremities of the magnet, therefore, the parts have a cooperative relation such that flux passes downwardly from one pole of the magnet into one or more of the fingers 14 on 80 the armature and through other fingers, to the other pole of the magnet. The flux so conducted passes twice through the skirt of the indicator. When the armature rotates these concentrated lines of force are caused 85 to traverse the metal of the indicator in the direction of rotation of the armature, so as to produce an inductive drag upon the indicator 90 in a well-known manner.

The relation of the parts described is such 95 as to permit the indicator to have a suitable form for the display of numerals, while the armature may be mounted directly upon a horizontal drive shaft, thus dispensing with the use of gearing or other undesirable driving connections. At the same time, the indicator may be of the simplest form, with its pivot staff mounted in stationary bearings 100 without the necessity of relatively delicate overhanging arms. Furthermore, ample space is provided for an odometer 15, visible through the face plate of the instrument in the usual position. This odometer may con- 105

veniently be driven by power derived from the drive shaft 13 through a worm wheel 17. The construction of the odometer and of its drive mechanism is not fully shown and described herein, since it constitutes no part of the invention claimed.

Although the magnet 10 is approximately circular in general form, so as to permit it to be of as great a length as possible, its polar extremities are preferably bent downwardly somewhat, as shown in Fig. 2, so as to secure a minimum air gap between the magnet and the indicator at this point.

It will be understood that where certain parts are shown and claimed as having the relation of upper and lower, horizontal and vertical, etc., these terms are used as descriptive merely of the relative positions of the parts since the parts so associated will operate in any absolute position.

The invention claimed is:

1. In a speedometer, the combination of a spring-controlled, pivotally mounted indicator, with an electrically conductive conical skirt, a magnet, in the form of an open ring, with its ends overlapping and lying close to the outer surface of the rear part of said skirt, and a rotary armature, having flux-concentrating projections of magnetic material, journalled in position to approximate the inner surface of the rear part of the skirt the axis of rotation of the armature forming a substantial angle with the pivotal axis of the indicator.

2. In a speedometer, the combination of a 35 housing of a form generally cylindrical about a horizontal axis, a magnet, of substantially circular form, with a gap and two polar extremities at its upper part, the magnet being approximately coaxial with the housing 40 and fixed in the rear part of the housing, a rotary armature, having flux-concentrating projections, of less diameter than the magnet and journalled on a horizontal axis so located that the uppermost part of the armature 45 moves close to the polar extremities of the magnet, a pivot-staff, in front of the magnet and the armature, mounted to turn upon an axis upwardly and forwardly inclined, and an indicator, mounted on said pivot-staff, 50 having a conical conductive skirt of which the rear part projects into the space between the adjacent parts of the magnet and the armature.

3. In a speedometer, the combination of a 55 spring-controlled indicator, with an electrically conductive conical skirt, pivotally mounted on an inclined axis, a magnet with its polar extremities lying close to one surface of said skirt at its rearmost part, and a rotary armature, having flux-concentrating projections of magnetic material, journalled on an axis forming a substantial angle with that of the indicator and in position such that said projections revolve in a path approximating the surface of said skirt opposite that to which the magnet-poles are adjacent.
